UNITED STATES PATENT OFFICE.

THOMAS M. DANIELS, OF CHICAGO, ILLINOIS.

TORPEDO-GUARD.

1,202,810.

Specification of Letters Patent. Patented Oct. 31, 1916.

Application filed September 24, 1915. Serial No. 52,343.

To all whom it may concern:

Be it known that I, THOMAS M. DANIELS, a citizen of the United States, residing at Chicago, in the county of Cook and State of Illinois, have invented a certain new and useful Torpedo-Guard, of which the following is a full, clear, and exact description, reference being had to the drawings appended hereto.

10 My invention relates to torpedo guards for vessels, and has reference more particularly to that type of guard designed for extension outwardly a sufficient distance from both sides of the vessel so as to explode by 15 contact torpedoes and mines which otherwise would contact with the hull of the vessel.

One of the primary objects of the invention is the provision of an improved torpedo 20 guard, composed of hinged sections, having the capability of easy manufacture and ready assemblage for application to the sides of the vessel. Another object is to provide such a guard which may be readily taken 25 apart and stowed away in a minimum of space on the vessel, and adapted when assembled to be quickly lowered over the sides of the vessel for immediate operative use. A further object of my invention is to produce a device of this character which may be 30 employed while the vessel is under way, and without materially retarding its progress.

A still further object is to cheapen the cost 35 and simplify the construction of such torpedo guards. My invention also contemplates certain novel details of construction and arrangement of parts of my improved device whereby certain objects are attained, as will be more fully described hereinafter 40 and pointed out in the claims.

The foregoing, together with such other objects as are incident to my invention, I obtain by means of a construction illustrated in preferred form in the accompanying 45 drawings, wherein:

Figure 1 represents a pictorial view of a vessel illustrating the application thereto of my improved torpedo guard.

Figures 2 and 3 are plan views of a portion 50 of the guard showing its relation with the side of the vessel.

Figure 4 is a view in elevation of the inner face of a portion of the guard shown in Figure 3.

55 Figures 5 and 6 represent views of the front and rear end plates of the guard.

Referring more particularly to Figure 1 of the drawings, it will be seen that my torpedo guard is composed of a series of sectional metallic plates which extend to protect both sides from the bow to the stern of the vessel, and to which, if desired, a lower supplementary series of plates may be attached and preferably in a manner so as to break joints with what would then be 65 the upper series of plates.

In carrying out my invention, I provide a plurality of sectional plates 10 hingedly connected together at their vertical side margins. Each plate, accordingly, is formed 70 at one side margin with eyes 11 and at the other side margin with eyes 12 arranged to interfit with the eyes 11 of the next adjacent plate 10 for the reception therethrough of the connecting pintle 13.

75 In order to maintain the plate sections at a suitable distance from the side of the vessel, I provide a plurality of outwardly extending booms or arms 14, each of which has at its outer end eyes 15 arranged to interfit with the eyes 11 and 12 and through which the pintle 13 also extends to hingedly connect the plates and arm together as in the manner shown in Figure 4. The pintle is formed with a head 13', and with a shoulder 13" adapted to rest on the upper eye 12, the numeral 20 indicating a spring-clip carried on the plate so that its free end 20" engages the pintle intermediate its head and shoulder so as to maintain the pintle against 90 vertical displacement in either direction. A loop 21 is formed on the inner face of the plate, and if desired additional loops 21" may also be provided for a purpose herein- 95 after more fully described.

At the inner end of the arm 14 are spaced knuckles 16 through which is passed a rod 17 carrying at each end a roller device 18 which slidably engages the side of the vessel. The numeral 19 indicates a stay arm having 100 a forked or bifurcated inner end portion 19" engaged with that portion of the rod 17 intermediate the knuckles 16, and a bent free end portion 19' adapted to engage with the loop 21. When thus engaged the arm 14 lies 105 at right angles to the plane of the side of the vessel and of the guard; as shown in Figure 2, and consequently the guard is then at its greatest extended position. Should it be desired to reduce the distance 110 between the vessel and its guard, this may readily be accomplished by manipulating the

bent end 19' of the stay-arm to engage with one of the supplementary loops 21^a, as in the manner indicated in Figures 3 and 4.

After the plates have been assembled into the complete guard, the latter may be quickly lowered to and suspended in its operative position by means of the davits 22 and chains 23, or similar devices, the arrangement permitting the lowering or raising of the guard in line with the free board of the vessel at times when torpedo attack is not anticipated or when the vessel is clear of mine-fields. Preferably each sectional plate 10 is suspended by a chain; and the raising or lowering operation of the guard is greatly facilitated by the provision of the roller devices 18 which, as already indicated, are carried by the booms 14 at their inner ends to slidably contact with the vessel's sides during these operations.

Coöoperating with the booms and suspension means with a view to aid in maintaining the relation of the torpedo guard with the vessel, the forward plate 24 is bent to assume the angular conformation illustrated in Figure 5, and is provided with eyes 24^a at its side edges by which it may be connected with the next adjacent plates. It is considered desirable that the degree of bend be somewhat greater than the angle presented by the bow of the vessel, so that the plate may have easy movement during the raising and lowering operation of the guard. Furthermore, I provide a rod or strap 25, adjacent the stern of the vessel, and on both sides thereof. This rod rigidly depends from the upper structure and passing through the eyes 12 of the rear end plate, see Figure 6, guides said plate during vertical movement and serves to maintain it in a fixed definite location when the guard is operatively positioned. The rods may be secured to the vessel in any manner considered preferable, and each desirably is formed with the lower offset portion 26 upon which the bottom eye 11 of the rear plate may rest.

The plates of the supplementary series are indicated by the numeral 27, and are carried by the plates 10, preferably being arranged to break joints with the latter, in the manner shown clearly in Figure 4 of the drawings. Openings 28, 28 are formed adjacent the lower edge of the plate 10, and fastened at one end of the plate adjacent each opening 28 is a spring clip 29 having its other end extending across said opening. The lower plates in turn are correspondingly provided on their inner faces, adjacent their upper margins, with headed studs 30, which, when the plates 10 and 27 are brought together in the lap relation shown in Figure 4, extend through the openings 28 and lock with the plate body and spring clip 29.

The plates 10 and 27 are respectively

alike and interchangeable, whereby in the event of partial or total destruction of one or more sections, the guard may be quickly raised and other plate sections substituted therefor. This substitution is facilitated by the pintle connection between the booms and plates, since withdrawal of the pintle only requires the preliminary deflection of the spring clip end 20 to clear the pintle shoulder 18^a.

From the foregoing, the essential features, elements and operation of my improved device, together with its simplicity and other advantages thereof, will be clearly apparent to those skilled in the art.

I do not desire to be understood as limiting myself to the precise details of construction and arrangement shown, as it is manifest that variations and modifications may be made in the features of construction and arrangement in the adaptation of the device to various conditions of use without departing from the spirit and scope of my invention and improvements. I therefore reserve the right to all such variations and modifications as properly fall within the scope of my invention and the terms of the following claims.

Having thus described my invention and illustrated its use, what I claim as new and desire to secure by Letters Patent, is the following:

1. In a torpedo guard, the combination of a plurality of associated vertically disposed guard sections, an outwardly extending boom therefor, connecting means for the adjacent vertical side margins of the sections, said boom having a pivotal connection therewith whereby the vertical disposition of the sections is maintained, a device associated with said boom for maintaining its outwardly extending relation with the sections, and means for raising and lowering said sections.

2. In a torpedo guard for vessels, the combination of a plurality of metallic guard sections, and a boom for the sections, adjacent ends of said boom and sections being pivotally connected together at a plurality of points in substantially the same vertical plane.

3. In a torpedo guard for vessels, the combination of a plurality of vertically disposed metal guard sections, and an outwardly extending boom for the sections, adjacent ends of said sections and the outer end of said boom being pivotally connected together in a common vertical axis to maintain the vertical disposition of the sections.

4. In a device of the character described, the combination of a plurality of guard sections adapted for disposition in substantial parallelism with the side of the vessel when operatively positioned, a pivot pin connecting adjacent vertical side margins of

- the sections, and a boom extending outwardly from the side of the vessel toward the sections and having an extended bearing engagement with said pin at its outer end.
5. In a sectional torpedo guard for vessels, the combination of a plurality of metallic guard sections, a boom extending outwardly from the side of the vessel toward the sections, a common connecting device for 10 the boom and sections, and means coöperating with said boom for maintaining the sections in operative relation with the side of the vessel.
6. In a torpedo guard for vessels, the 15 combination of a plurality of guard sections, an outwardly extending boom therefor, a common vertically disposed connecting member for pivotally connecting together the inner adjacent ends of said sections and the outer end of said boom, a stay arm adjustably extending between the inner end of the boom and one of the sections, and means for lowering and raising said sections, substantially as described.
- 20 7. In a device of the character described, the combination of a metallic guard section, an outwardly extending boom connected therewith at its outer end and having a roller device on its inner end, and means for raising and lowering said section and boom.
8. In a device of the character described, the combination of a metallic guard section having a loop formed on its inner face, an outwardly extending boom therefor, a pintle 35 connecting the outer end of the boom with the section, and a stay-arm carried by the boom and adapted to engage in said loop, substantially as described.
9. In a device of the character described, 40 the combination of a plurality of metallic guard sections, an outwardly extending boom therefor, adjacent ends of said boom and sections being pivotally connected to-
- gether, a stay-arm extending from the boom to one of the sections, and suspension means 45 for said sections.
10. In a device of the character described, the combination of a plurality of guard sections, an outwardly extending boom therefor, adjacent ends of said boom and sections 50 being pivotally connected together, a stay-arm for one of said sections, a roller device carried by said boom, and means for raising and lowering said sections.
11. In a torpedo guard for vessels, the 55 combination of a plurality of superposed metallic guard sections connected together at their horizontal edge margins, and an outwardly extending boom for the sections, the adjacent ends of the upper guard sections being pivotally connected together and the lower guard sections being arranged to break joints with the upper sections, substantially as described.
12. A torpedo guard for vessels comprising 60 a series of pivotally connected metallic guard sections and booms, the bow section being bent to engage with the bow, a guide rod for the rear guard section, and means for raising and lowering the sections. 65
13. In a torpedo guard for a vessel, the combination of a plurality of associated and vertically disposed guard sections, an outwardly extending boom pivotally connected therewith and arranged to maintain said 70 sections at the desired distance from the side of the vessel, said sections having their vertical side margins connected together in a manner permitting relative play of the sections lengthwise of the vessel, and means 75 operating to maintain the boom in its outwardly extending relation with the sections.

In testimony whereof I have hereunto signed my name.

THOMAS M. DANIELS.
